COMBINATION REAR SIGHT AND EJECTOR
FOR FIREARMS

John C. Garand, Springfield, Mass.

Application March 3, 1947, Serial No. 732,041

4 Claims. (Cl. 42—1)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a combination rear sight and ejector for a firearm.

This application is a continuation-in-part of my application Serial No. 618,805, filed September 26, 1945, for Firearms.

It is an object of this invention to provide a rear sight for a firearm having a plurality of sight blades whereby the sight may be quickly adjusted for any range.

Another object of this invention is to provide a rear sight for a firearm which can be selectively adjusted for a plurality of ranges and which is yieldingly held in each of such positions by the ejector of the firearm.

The specific nature of the invention as well as other objects and advantages thereof will clearly appear from a description of a preferred embodiment as shown in the accompanying drawings in which:

Fig. 1 is a partial side elevational view of a firearm with the receiver shown partly broken away to illustrate the ejector engaging the base of a cartridge and of the rear sight.

Fig. 2 is an enlarged detail top view of the rear sight.

Fig. 3 is an enlarged detail front elevational view of the rear sight.

Fig. 4 is a partial cross-sectional view taken along the line 4—4 of Fig. 3 showing the sight positioning slots in the pin of the sighting element.

This invention essentially comprises a rear sight having a sight element rotatably mounted in a sight base, such sighting element having a plurality of sight apertures adapted for use at different ranges. The sighting element is selectively secured in any one of a plurality of positions by the ejector of the firearm.

The rear sight 15 shown in Fig. 1 comprises a substantially rectangular base 16 and a sighting element 17. On top of such base there is integrally formed a transverse arcuately shaped raised portion 18. A transverse hole 19 is provided in raised portion 18 in which is inserted sighting member 17 in a manner as will be later described. The bottom of base 16 is arcuately shaped as shown at 20 in order that such base may be placed on top of a tubular receiver 21 of firearm 22 shown in Fig. 1.

Base 16 is secured to receiver 21 by a screw 23. A vertically disposed hole 24 in sight base 16

permits such screw to be inserted therethrough. A longitudinal slot 25 is provided on the right side of base 16 as shown in Fig. 3 to accommodate an ejector 26 for a purpose to be presently described.

Sighting element 17 comprises an L-shaped member 27 and an integral pin 32 disposed at right angles to sighting element 17. Each arm of such L-shaped member terminates in circular end portions 28 and 29 and apertures 30 and 31 are respectively provided therein. Aperture 31 is disposed at a greater distance from the axis of pin 32 than aperture 30 in order to adapt the sight for more than one range of sighting. Adjacent the end of pin 32, shallow slots 33 and 34 are milled therein and are disposed parallel to the respective arms having ends 28 and 29. An annular groove 44 is provided on pin 32 as shown in Figs. 2 and 3. Pin 32 of sighting element 17 is inserted in hole 19 of base 16 and sighting element 17 is rotatably secured thereto by screw 23 which engages annular groove 44. When pin 32 is inserted in hole 19, sighting element 17 is then disposed to one side of the axis of the firearm thus producing an offset sighting means. The front sight (not shown) obviously must be offset correspondingly.

Ejector 26 is a spring-like member constructed of wire having one end 35 bent at substantially 90° to the body portion 37 thereof while the other end 36 is bent downwardly and outwardly as shown in Fig. 2. The body portion 37 is somewhat arcuately shaped as shown in Fig. 2, to provide a spring action.

35 A longitudinal groove 38 is provided on top of receiver 21 to receive ejector 26. Groove 38 is preferably deeper at the forward end of receiver 21, as shown at 39, to permit end 36 of ejector 26 to engage a longitudinal groove 40 provided 40 on a firearm bolt 41 slidably contained within receiver 21. In this manner the extreme end of ejector 26 can contact the base of an empty cartridge case 42 to eject such case in a manner to be later described. End 35 of ejector 26 is inserted in a radially disposed hole 43 in receiver 21 thereby securing such ejector to the receiver.

When ejector 26 is assembled to the firearm, as shown in Fig. 1, such ejector lies within slot 25 of base 16 and when in such slot the body portion 37 of ejector 26 engages one of the slots 33 or 34 depending upon which aperture is raised upwardly at the moment. For the above reason and due to the arcuate shape of body portion 37 of ejector 26, which produces a spring-like action in ejector 26, a force is exerted against pin

32 thereby yieldingly securing sighting element 17 in one of two positions.

For ranges up to approximately 100 yards, aperture 30 should be raised to the position shown in Fig. 1. Such is accomplished by rotating circular end portion 29 of the L-shaped member in a counterclockwise direction. The other sighting aperture is raised by merely forcing end portion 28 in a clockwise direction which will permit sighting at ranges up to approximately 300 yards. 10

When bolt 41 is retracted, either manually or by automatic operation of the firearm, the base of cartridge case 42 held against the face of bolt 41 strikes the end 36 of ejector 26 whereupon the cartridge case 42 is ejected from the gun. 15

From the foregoing description it is readily apparent to those skilled in the art that there is here provided a simple rear sight easily adjustable for various elevational requirements including an ejector to positively eject empty cases from the firearm which is also utilized to yieldingly secure the rear sight in a plurality of positions.

I claim:

1. In a firearm having a receiver and a bolt reciprocating therein, the improvement comprising, an adjustable sight secured to the receiver, said sight being constructed and arranged to be selectively positioned in any one of a plurality of sighting positions, and a wire-like spring mounted in the receiver, said spring having a first portion engaging said adjustable sight to resiliently secure said sight in any selected position, said spring also having a second portion constructed and arranged to extend within the receiver into the path of the bolt to serve as a cartridge ejector. 25

2. In a firearm having a receiver and a bolt reciprocating therein, the improvement comprising, a rear sight base secured to the receiver, said base having a hole therethrough, a pivot pin pivotally mounted in said hole, a plurality of angularly spaced sighting arm members rigidly secured to said pivot pin, said pivot pin having flats arranged in angularly spaced relation to said sighting arm members, and a wire-like spring mounted adjacent the receiver, said spring having a first portion resiliently engaging one of said flats on the pivot pin whereby said sighting arm members are resiliently maintained in a selected angular position, said spring also having a second portion constructed and arranged to extend

within the receiver into the path of the bolt to serve as a cartridge ejector. 4

3. A firearm comprising, a receiver, a bolt reciprocating therein, a rear sight base secured to said receiver, said base having a hole therethrough, a pivot pin pivotally mounted in said hole, a plurality of angularly spaced sighting arm members rigidly secured to said pivot pin, said pivot pin having flats arranged in angularly spaced relation to said sighting arm members, and a wire-like spring mounted adjacent said receiver, said spring having a first portion resiliently engaging one of said flats on the pivot pin whereby said sighting arm members are resiliently maintained in a selected angular position, said spring also having a second portion constructed and arranged to extend within said receiver into the path of said bolt to serve as a cartridge ejector, said bolt having a longitudinal recess on the surface thereof to accommodate said second portion of said spring. 10

4. In a firearm having a receiver, a bolt reciprocating therein, and a rear sight assembly secured to the receiver, said assembly comprising, a base, said base having a transverse hole therethrough, a pivot pin pivotally mounted in said hole, a plurality of angularly spaced sighting arm members rigidly secured to said pivot pin, said pivot pin having flats arranged in angularly spaced relation to said sighting arm members, said base having a longitudinal slot in its surface adjacent the receiver, said slot intersecting said pin hole in alignment with said flats, the receiver having a magazine well in longitudinal alignment with the rear sight assembly, the receiver having an external longitudinal groove, said groove extending under the rear sight base assembly adjacent said slot and opening into said magazine well, and a wire-like spring located in said groove, 20 said spring having a first portion extending into said slot in the rear sight base assembly and resiliently engaging one of said flats on said pivot pin whereby said sighting arm members are resiliently maintained in a selected angular position, 25 said spring also having a second portion constructed and arranged to extend within the receiver into the path of the bolt to serve as a cartridge ejector, the bolt having a longitudinal recess on the surface thereof to accommodate said 30 second portion of said spring. 45

JOHN C. GARAND.
